(57) **CLAIM**

The ornamental design for an instrument panel for an automobile, as shown and described.

DESCRIPTION

FIG. 1 is a left-front side perspective view of an instrument panel for an automobile;

FIG. 2 is a right-front side perspective view thereof;

FIG. 3 is a front view thereof;

FIG. 4 is a plan view thereof;

FIG. 5 is a right side view thereof; and,

FIG. 6 is a left side view thereof.

The broken lines in the drawings illustrate portions of the instrument panel for an automobile that form no part of the claimed design.

1 Claim, 6 Drawing Sheets
